CLAIM

USPC **D7/393**; D7/392.1; D7/397

The ornamental design for a pitcher top, as shown and described.

(58) **Field of Classification Search**

DESCRIPTION

USPC D23/207, 209; D7/19, 323, 391, 392, D7/392.1, 393, 396.2, 397, 398, 399, 443, D7/447, 449, 509, 510, 511, 629; D9/443, D9/447, 450, 451, 452, 453, 503, 504, 523, D9/527, 552, 561, 761; 222/475.1, 465.1; 215/387, 388, 11.1, 41

FIG. 1 is a top, front and side perspective view of a pitcher top embodying the new design.

CPC A47G 19/00
See application file for complete search history.

FIG. 2 is a top, back and side perspective view thereof.

FIG. 3 is a front view thereof.

FIG. 4 is a back view thereof.

FIG. 5 is a side view thereof, the opposite side being a mirror image.

FIG. 6 is a top view thereof; and,

FIG. 7 is a bottom view thereof.

Broken lines are used to illustrate features of the pitcher top which form no part of the claimed design. The dot-dot-dash line is used to illustrate a boundary of the claim and forms no part of the claimed design.
